VEHICLE MOUNTED GUN AND PERISCOPE
MOUNTING THEREFOR

Marvin J. Minter, Detroit, Mich.

Application May 22, 1945, Serial No. 595,232

8 Claims. (Cl. 89—40)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates generally to a gun sight linkage and more particularly to linkage interconnecting a gun and a viewing device to coordinate their movement.

Military combat tanks are generally provided with a bow machine gun mounted in the front armored wall of the tank and aimed and fired by a gunner seated within the tank. To enable the gunner to properly aim the gun, the present invention provides a swivel mounted periscope in the hatch cover located directly above the gunner's seat and connected to the machine gun in such a manner as to provide coordinated swiveling movement of the gun and the periscope.

It is, therefore, a principal object of the invention to provide a pivotally mounted gun and a pivotally mounted viewing device interconnected by linkage arranged to provide coordinated pivotal movement of the gun and viewing device.

Another object of the invention is to provide a gun and a separate viewing device each mounted for universal pivotal movement and interconnected by the pair of parallel rods in such a manner that pivotal movement of the gun effects a corresponding pivotal movement of the viewing device.

It is a further object to provide quick detachable universal connections which may be used between the linkage and the gun and viewing device to permit the linkage to be quickly disconnected. It is also an object to enable the linkage to be automatically released or disconnected when the hatch cover is opened in order to permit free access to the hatch.

Other objects and advantages of the present invention will be made more apparent as this description proceeds, particularly when considered in connection with the accompanying drawings, in which:

Figure 1 is a vertical longitudinal cross sectional view through a portion of the vehicle illustrating the present invention;

Figure 2 is a plan view of the gun, periscope, and linkage of Figure 1 separated from the vehicle;

Figure 3 is a longitudinal cross sectional view through one of the quick detachable connections;

Figure 4 is a cross sectional view taken substantially on the plane indicated by the line 4—4 of Figure 3, and

2

Figure 5 is a cross sectional view taken substantially on the plane indicated by the line 5—5 of Figure 3.

Referring now more particularly to the drawing, the reference character 10 designates a portion of a tank having an armored front wall 11, the lower portion of which is substantially vertical, and a substantially horizontal armored upper wall 12 provided with a hatch opening 13. A hatch cover 14 is pivoted to the front wall 11 by the hinge 15 and may be opened to provide for entry into the interior of the tank and closed to afford protection to the gunner.

The front wall 11 is provided with an aperture 16 to permit the bow machine gun 17 to project therethrough. The cradle 18 of the gun is provided with a ball joint 19 mounted for swiveling movement in a socket 20 bolted to the front wall 11 of the tank. A shield 21 is provided upon the forward portion of the gun to protect the swivel joint from shell fire or the like.

The foregoing construction, which is conventional, enables the gun operator to swivel the gun in all directions so that any target in front 25 of the tank may be fired upon.

To protect the gunner from enemy fire, and yet to enable him to accurately aim and fire the gun, I have provided a periscope 22 which is mounted in the hatch cover 14 for swiveling movement. The hatch cover 14 has a circular opening 23 therein provided with an annular rib 24. The rib 24 is embraced between a pair of circular plates 25 and 26 suitably clamped together and mounted for rotation in the opening 23. The plates 25 and 26 are provided with openings 27 and 28 respectively, adapted to receive the enlarged upper end 29 of the periscope holder 30.

The periscope holder 30 is pivotally mounted 40 for movement about a transverse axis by means of a pivot pin 31 journaled in suitable openings (not shown) in the plates 25 and 26. The front and rear edges of the openings 27 and 28 are arcuate for cooperation with the arcuate front 45 and rear walls of the enlargement 29 of the periscope holder 30.

From the foregoing it will be noted that the periscope 22 is mounted for universal pivotal movement by means of the pivot pin 31 which 50 permits the periscope to pivot about a transverse horizontal axis and the rotatable circular plates 25 and 26 which permit movement of the periscope about a vertical axis.

The periscope is of conventional construction 55 and permits the gunner's line of sight to be dis-

placed from the line 32 within the tank to the line 33 outside the tank and parallel thereto.

Formed integral with the cradle 18 of the machine gun 17 are a pair of transversely extending arms 34 and 35 each terminating in a ball joint 36. The periscope 22 is likewise provided with a pair of arms 37 and 38 extending rearwardly and outwardly therefrom and bolted at 39 to the opposite sides 5 of the periscope holder 30. The arms 37 and 38 likewise terminate in ball joints 40.

Interconnecting the arms 34 and 35 of the gun with the arms 37 and 38 respectively of the periscope are a pair of parallel rods 41 and 42 respectively. The opposite ends of the rods 41 and 42 are provided with quick detachable connecting units 43 attached to the ball joints 36 and 40 upon the ends of the rods and forming therewith universal pivotal connections.

Before describing in detail the quick detachable connecting units 43, it should be noted that the geometry of the construction is such that the rods 41 and 42 are parallel to each other and also are parallel to a line 44 interconnecting the points about which the gun and periscope swivel. As best seen in Figure 2, the arms 34 and 35 are of equal length so that the ball joints 36 are disposed equal distances on opposite sides of the centerline 45 of the gun. Likewise the arms 37 and 38 are symmetrical in size and location so that the ball joints 40 are located equal distances on opposite sides of the centerline 45.

The gun and periscope are arranged so that the centerline 45 of the gun is at right angles to the centerline 46 of the periscope at all times, with the result that the line of sight 32-33 through the periscope is always parallel to the centerline 45 of the gun. Suitable markings may be provided on the periscope to assist the gunner in aiming.

Referring to Figure 1, it will be noted that a plane through the swivel point 47 of the gun and the ball joints 36 defines a predetermined angle 48 with the axis 45 of the gun. An angle 49 of equal size is formed by a plane through the swivel point 50 of the periscope and the ball joints 40 and a line passing through the swivel point 50 parallel to the line of sight 32-33. Furthermore the ball joints 36 and 40 are located equal distances from the swivel points 47 and 50 of the gun and periscope respectively.

With the construction discussed above, perfect symmetry is provided and the swiveling movement of the gun and periscope are coordinated with each other so that a pivotal movement of the gun in any direction affects a corresponding movement of the periscope and maintains the gun centerline 45 and the line of sight 32-33 always parallel.

Although the present invention can be used with an ordinary ball and socket joint between each end of the rods 41 and 42 and the adjacent ends of the arms 34, 35, 37 and 38, to provide for universal pivotal movement therebetween, the use of the quick detachable connecting units 43 is preferable. These units permit the linkage interconnecting the gun and periscope to be quickly and easily disconnected so that the periscope may be used independently of the gun if desired, and also so the linkage will not be in the way when the hatch cover 14 is open and the gunner is entering or leaving the tank through the hatch opening 13.

As best seen in Figures 3, 4 and 5, each quick detachable connecting unit 43 comprises an ex-

tended frame 51 having spaced side plates 52 and 53 having their bottom edges interconnected by a web 54. Each side plate 52 and 53 is provided with a pair of spaced apertures 55 adapted to receive a pin 56 held in position by a head 57 at one end thereof and a cotter pin 58 at the opposite end. Pivotally mounted on the pin 56 between the side plates 52 and 53 of the frame are a pair of trigger-like lever members 59. Each trigger-like lever member 59 has a bore 60 receiving therein one end of a respective one of a pair of hollow sleeves 61 the latter having their other ends internally threaded and spaced apart when in the normal position as shown in Figure 3.

Adjustably mounted within the threaded end of each sleeve 61 is a socket member 62 provided with a concave spherical shaped indentation 63 upon one end. The indentations 63 of the socket members 62 cooperate with each other to form a socket engaging the spherical head 64 of the ball joints 36 or 40.

Adjustment of the socket members 62 toward and away from each other is accomplished by turning the latter within the sleeves 61. Screwdriver slots 65 are provided in the socket members to facilitate this operation. The sleeves 61 are provided with a plurality of angularly spaced holes 66 to receive cotter pins 67 which pass through the slots 65 and hold the socket members 62 in their adjusted positions.

The lower end of each trigger-like lever member 59 is provided with a socket 68 for receiving the opposite ends of a compression spring 69. The spring 69 operates to urge the trigger-like lever members 59 apart and normally maintains the various parts of the unit in the position shown in Figure 3 in which the sleeves 61 are seated upon the web 54 of the frame 51. In this position the socket members 62 are in axial alignment 40 and in engagement with the spherical ball 64 of the ball joints.

The quick detachable connecting units 43 are disengaged from the ball joints by grasping the trigger-like lever members 59 and moving the latter toward each other against the action of spring 69. This pivots the trigger-like lever members 59, sleeves 61, and socket members 62 about the pivot pins 56 and, with reference to the position of the parts as shown in Figure 3, moves the spherical indentations 63 of the socket members 62 upwardly and out of retaining engagement with the spherical head 64 of the ball joints. Reassembly with the ball joints is easily accomplished by operating the trigger-like lever members 59 to separate the socket members 62 and then, after the head 64 of the ball joints is inserted therebetween, releasing the trigger-like lever members and permitting the spring 69 to move the socket members into engagement with the ball.

The side plates 52 and 53 of the frame 51 are provided with extensions 70 at one end adapted to receive therebetween a hexagonal member 71, the latter being welded between the extensions 70. The hexagonal members 71 are internally threaded to receive the threaded ends of the rods 41 and 42, thus adjustably joining the rods to the connecting units. It will be seen that each rod forms with its pair of hexagonal members 71 a turnbuckle of simple and strong construction. Lock nuts 72 are provided upon the rods to lock the latter in their adjusted positions.

In addition to permitting the rods 41 and 42 to be disconnected from the gun and the periscope

by a simple manual operation, the units 43 permit the rods to be automatically disconnected from the arms 37 and 38 of the periscope when the hatch cover 14 is opened. As best seen in Figure 1, the hatch cover 14 is pivoted on hinges 15 at its forward edge so that upon upward pivotal movement of the hatch cover the rods 41 and 42 are carried forward and eventually strike the inclined portion of the front wall 11 of the tank. Further movement of the hatch cover after the rods have engaged the wall pulls the ball joints 40 from between the socket members 62, this being permitted by the pivotal mounting of the sleeves 61 and trigger-like lever members 59 and the resilient spring 69 between the trigger-like lever members.

This automatic release is a valuable safety factor since it permits the gunner to make an emergency exit through the hatch without stopping to disconnect the rods 41 and 42 from the periscope.

Another advantage of the present construction is that its simplicity and rigidity eliminates to a large degree vibration which would otherwise be present between the gun and periscope. The vibration can be decreased further, if desired, by the insertion of a vibration dampener of conventional design in rods 41 and 42.

Although I have shown and described certain embodiments of the invention, it will be understood that I do not wish to be limited to the exact construction shown and described, but that various changes and modifications may be made without departing from the spirit and scope of my invention as defined in the appended claims.

What I claim is:

1. In a device of the character described, a gun mounted for universal pivotal movement about a pivot point, a pair of arms extending from said gun, a viewing device mounted for universal pivotal movement about a pivot point spaced from said gun pivot point, a pair of arms extending from said viewing device, and a pair of parallel rods interconnecting the said arms on the gun with the said arms on the viewing device, said rods having releasable universal connections with said arms and providing coordinated pivotal movement of said gun and said viewing device.

2. In a device of the character described, a gun mounted for universal pivotal movement about a pivot point, a viewing device mounted for universal pivotal movement about a pivot point spaced from said gun pivot point, a pair of spaced parallel rods each extending parallel to a line connecting the pivot points of said gun and said viewing device, and releasable means universally pivotally connecting the opposite ends of said rods to said gun and said viewing device respectively so that pivotal movement of said gun effects a corresponding pivotal movement of said viewing device.

3. In a device of the character described, a pivotally mounted gun, a pivotally mounted viewing device spaced from said gun, a rod extending parallel to and spaced from a line connecting the pivot points of said gun and said viewing device, and quick releasable universal connections pivotally connecting the opposite ends of said rod to said gun and said viewing device respectively so that pivotal movement of said gun effects a corresponding pivotal movement of said viewing device, each of said connections comprising a frame at one of said ends of said rod, a pair of spaced trigger-like lever members pivotally mounted on said frame, sleeves carried by said

lever members, sockets adjustably mounted in said sleeves and cooperating to receive a ball joint, and a compression spring mounted between said lever members and urging said sockets toward each other.

4. In a device of the character described, a gun mounted for universal pivotal movement about a pivot point, a viewing device mounted for universal pivotal movement about a pivot point spaced from said gun pivot point, a pair of parallel rods, a quick releasable ball and socket joint at one end of each of said rods connecting the latter to said gun at a predetermined distance from the pivot point of the latter, and a quick releasable ball and socket joint at the opposite end of each of said rods connecting the latter to said viewing device and spaced from the pivot point of the latter a distance equal to the distance between the said one end of said rods and the gun pivot point so that a pivotal movement of said gun in any direction effects a corresponding movement of said viewing device.

5. In a combat vehicle having an armored wall and a hatch cover each provided with an aperture, a swivel mounted gun projecting through the aperture in said wall, a swivel mounted periscope projecting through the aperture in said hatch cover, a pair of spaced parallel rods within said vehicle each extending parallel to a line connecting the swivel points of said gun and said periscope, and quick releasable ball and socket connections joining the opposite ends of said rods to said gun and said periscope and arranged to provide coordinated swivelling movement of said gun and said periscope.

6. In a combat vehicle having a substantially vertical armored wall and a substantially horizontal hatch provided with a pivoted hatch cover, a swivel mounted gun projecting through said wall, a swivel mounted periscope projecting through said hatch cover, a pair of parallel rods within said vehicle, and quick releasable means universally connecting the opposite ends of said rods to said gun and said periscope to provide coordinated swivelling movement of said gun and said periscope, said quick releasable means providing for quick detachment of said rods from said periscope to permit free access to said hatch.

7. In a combat vehicle having a substantially vertical armored wall and a substantially horizontal hatch provided with a pivoted hatch cover, a swivel mounted gun projecting through said wall, a swivel mounted periscope projecting through said hatch cover, a pair of parallel rods within said vehicle, said rods being universally connected at opposite ends thereof to said gun and said periscope, and means for automatically releasing said rods from their connection with said periscope when the hatch cover is opened to permit free access to said hatch.

8. A quick detachable universal connection comprising a frame, a pair of spaced trigger members pivotally mounted on said frame, sleeves carried by said trigger members, sockets adjustably mounted in said sleeves and cooperating to receive a ball joint, a compression spring mounted between said trigger members and urging said sockets toward each other, and a stop on said frame limiting the pivotal movement of said trigger members, sleeves and sockets.
